HYDRAULIC POWER SYSTEM

Norman W. Taylor, Cleveland Heights, Ohio, assignor to The Warner & Swasey Company, Cleveland, Ohio, a corporation of Ohio

Application April 3, 1948, Serial No. 18,809

7 Claims. (Cl. 121—46)

1

This invention relates to a hydraulic power system valve, and particularly to a valve adapted to be employed in the hydraulic operating circuit to a hydraulic motor which actuates a movable element of an apparatus.

The apparatus with which the valve embodying the invention can be advantageously employed might be any type of apparatus wherein the hydraulic motor raises and lowers a movable element of the apparatus and which element is subject to different loads or forces at different times and particularly with respect to its lowering movement. As examples of apparatus wherein the valve may be advantageously employed reference is made without limitation to a hydraulic hoist, elevator, the hydraulically actuated pivoted boom of a derrick or of a material handling machine. Inasmuch as the valve may be employed with special utility in the operating circuit of a hydraulic motor that actuates the raising and lowering of a pivoted boom, it will be described herein with particular reference to such an environment. Especially is this the case where the weight of the load raised or lowered by the boom may be different at different times and also where the application of the load with respect to the pivotal axis of the boom may change for different operations of the boom.

An object of the invention is to provide an improved and novel valve for use in the operating circuit to a hydraulic motor that actuates the raising and lowering of a movable element of an apparatus and which valve ordinarily provides for a substantially constant predetermined rate of lowering movement or travel of the element at all times irrespective of the load acting on the element during the lowering movement.

Another object is to provide in the operating circuit to the hydraulic motor that actuates the raising and lowering of a movable element of an apparatus, a valve which ordinarily maintains during the lowering movement of the element a substantially constant rate of discharge from the exhaust side of the motor, and should back pressure reacting on the exhaust side of the motor develop in the valve in excess of a predetermined pressure, said valve will function automatically and momentarily to reduce from full line pressure the input pressure to the motor until the back pressure falls to or below said predetermined pressure.

2

Another object is to provide a valve which can be used in the operating circuit to a hydraulic motor that raises and lowers an element of an apparatus and which valve automatically provides for a faster raising operation of the motor and raising movement of the element than the lowering operation and movement thereof and also provides for a substantially constant speed lowering operation of the motor and lowering movement of the element, irrespective of the load applied to the element during its lowering movement.

A further object of the invention is to provide in the hydraulic raising and lowering operation of a movable element of an apparatus means for maintaining a substantially uniform lowering rate of movement of the element irrespective of loads, thus providing for safety of operation.

Further and additional objects and advantages not hereinbefore referred to will become apparent during the description of an embodiment of the invention which is to follow.

Referring to the accompanying drawing:

Fig. 1 illustrates said embodiment of the invention and shows the valve diametrically located in the operating circuit to a hydraulic motor; the section through the valve being taken substantially along line 1—1 of Fig. 2 and the two plunger valves in the valve being shown in their normal positions.

Fig. 1a is a sectional view of the valve shown in Fig. 1 but with the two valve plungers thereof moved automatically from their normal positions and into the positions they may momentarily have during lowering operation of the motor when the back pressure on the exhaust side of the motor exceeds a predetermined pressure and the line pressure on the input side of the motor is momentarily and automatically reduced substantially from full line pressure.

Fig. 2 is a sectional view taken substantially on line 2—2 of Fig. 1, and

Fig. 3 is a sectional view taken substantially on line 3—3 of Fig. 2.

The valve embodying the invention is shown arranged in the operating circuit to a hydraulic motor 10 of the reciprocating piston type. The piston 11 of the motor slides in the motor cylinder and actuates through a piston rod 12 the raising and lowering of an element 13 of an apparatus. This element 13 may be in the form of a

pivoted boom that is raised and lowered at different times under different load conditions. During raising operation of the motor 10 to raise the element 13 the piston 11 moves upwardly in the motor cylinder, as viewed in the drawing, while during lowering operation of the motor to lower said element said piston moves downwardly in the motor cylinder. The motor cylinder is provided adjacent its opposite ends with ports 14 and 15 to which are connected, respectively, hydraulic lines 16 and 17 that extend to the valve of the invention.

The said valve comprises a valve housing 18 having therein adjacent its lower end, as viewed in the drawing, an L-shaped chamber 19 and adjacent its upper end a chamber 20. The chamber 19 is connected to the line 16 and the chamber 20 is connected to the line 17. The valve housing 18 also is provided with a chamber 21. The chambers 19 and 21 of the valve housing are connected by lines 22 and 23, respectively, to any suitable form of selector valve for selecting the direction of operation of the motor.

In Fig. 1, and for purposes of illustration only, the line 22 is shown as connected to a port 24 and the line 23 to a port 25 formed in the housing 26 of a selector valve and communicating with the interior of said housing. The selector valve has rockably mounted therein a diametrically extending valve body 27 which is provided with a through passage 28 in communication at its midpoint with a supply line 29 extending from a suitable source of supply of hydraulic pressure medium. The valve body 27 may be rocked by a handle 30 to a position wherein the through passage 28 in the valve body is in communication with the port 24 and out of communication with the port 25 for lowering operation of the hydraulic motor or to a position wherein said through passage communicates with the port 25 and is out of communication with the port 24 for raising operation of the hydraulic motor. The interior of the valve housing is connected by a port 31 to an exhaust line 31a which functions for both of the operative positions of the valve body just referred to. Also the valve body might be moved to a third or idle position wherein the passage 28 is in communication with the exhaust port 31 while both ports 24 and 25 are out of communication with either the inlet or exhaust sides of the valve.

The valve housing 18 adjacent to the chamber 20 is shown as provided with a through passage closed at its opposite ends by threaded plugs 32 and 33 and forming a chamber 34 for a plunger valve 35 that is provided with three land portions 36, 37 and 38, which are slidable in said plunger valve chamber. A spring 39 of predetermined strength is mounted in a central recess of the plug 33 and bears against the right hand end of the plunger valve 35 as viewed in Fig. 1 and acts to maintain said plunger valve normally in the position shown in Fig. 1. The plunger valve chamber 34 in the normal position of the plunger valve 35 is in communication by means of a port 40 with the chamber 20. The plunger valve chamber 34 also when the plunger valve is in its normal position is in communication by means of a port 41 with a chamber 42. The chamber 42 is connected also to the left hand end of the plunger valve chamber 34, as viewed in the drawing by a small passage 43 which extends to the left side of the land 36 of the plunger valve when said valve is in its normal position.

The chamber 42 is also connected by a port 44

to the chamber 21, the effective area of the port 44 being controlled by the tapered end of a needle valve 45 having a threaded stem portion that is adjustably screwed in a threaded opening in the valve housing 18 and which portion projects outwardly of said housing. It will be understood that the needle valve 45, depending upon its particular adjusted position, controls the effective area of the port 44 and provides an adjustable orifice connection between the chambers 42 and 21. The needle valve 45 may be locked in adjusted position by means of a threaded cap 46 screwed onto the projecting threaded end of the needle valve.

The valve housing 18 is provided intermediate the chambers 19 and 21 with a circular recess extending into the body from one side thereof and forming a chamber 47 for a plunger valve 48 that is provided with spaced lands 49 and 50 slidable in the chamber 47. The open end of the recess or chamber 47 is closed by a threaded plug 51 which mounts a spring 52 of predetermined strength corresponding to the strength of spring 39 and which spring 52 bears against the right hand end of the plunger valve 48 and normally maintains said valve in the position shown in Fig. 1. The recess or plunger valve chamber 47 at its left hand end is connected by a port 53 to the chamber 42. The plunger valve chamber 47 is connected to the chamber 21 by a port 54 which in the normal position of the plunger valve 48 is closed by the land 50. The plunger or valve chamber 47 is also connected by a third port 55 with the chamber 19 and said port 55 is located at all times intermediate the lands 49 and 50.

The valve housing 18 intermediate the chambers 20 and 21 is provided with a bore 56 closed at its right hand end, as viewed in Fig. 3, by a plug 57 screwed into the valve housing. The bore 56 adjacent its left hand end, as viewed in Fig. 3, has a valve seat 58, it being noted that the left hand end of the bore 56 communicates through the valve seat with the chamber 21. The bore 56 adjacent the valve seat 58 communicates by a port 59 with the chamber 20, while said bore 56 adjacent its right hand end is also in communication with the chamber 20 by a port 60. A valve 61 is slidable in the bore 56 and is held seated on the seat 58 by a relatively weak spring 62, one end of which abuts the valve 61 and the other end of which extends into a recess formed in the plug 57.

The operation of the valve heretofore described will now be explained. It will be assumed that hydraulic pressure is on the through passage 28 of the selector valve body 27 and that said body is in the position shown in Fig. 1 and that the hydraulic motor 10 is operating in the lowering direction. It will further be assumed that the needle valve 45 has been adjusted to the desired adjustment and that the plunger valves 35 and 48 are in their normal positions as indicated in Fig. 1. At this time full line pressure is flowing from the selector valve 26 through line 22, chamber 19, line 16 and port 14 to the upper side of the piston 11 of the hydraulic motor. The hydraulic medium below the piston 11 is being exhausted through port 15, line 17 and into chamber 20. The hydraulic medium in chamber 20 acts through port 59 in conjunction with spring 62 to maintain the valve 61 on its seat 58 and thus to interrupt communication between the chamber 21 and chamber 20 by way of the bore 56. However, since the chamber 20 communicates with the plunger valve chamber 34 the hydraulic me-

dium beneath the piston 11 will be exhausted through the chamber 20, port 40 and pass between the lands 36 and 37 of the plunger valve 35 into the chamber 42. The exhausting hydraulic medium will then pass from the chamber 42, through the needle valve controlled port 44 into the chamber 21. It will be recalled that the needle valve controls the effective area of the port 44, and hence controls the rate of flow of the hydraulic medium through the port 44. The hydraulic medium exhausted to the chamber 21 then flows through line 23, port 25 to the interior of the selector valve and thence to the discharge line 31a. If the action of the full line pressure on the upper side of the piston 11, in conjunction with the load of the element 13 acting on the piston, tends to cause the piston to move in a lowering direction at a rate that will cause the hydraulic medium to exhaust into the chamber 42 faster than it can be exhausted therefrom to the chamber 21 through the needle valve controlled port 44, then back pressure will be created in the chamber 42 and such back pressure acting through the passage 43 on the left-hand end of the plunger valve 34 will overcome, when it reaches a predetermined pressure, the action of the spring 39 and shift the plunger valve 35 toward the right from the position shown in Fig. 1 to the position shown in Fig. 1a, wherein the land 36 of the plunger valve 35 closes the ports 40 and 41 and interrupts the exhaust of the hydraulic medium from the chamber 20. This back pressure that may be built up in chamber 42 also acts simultaneously through port 53 to shift plunger valve 43 against the predetermined resistance of the spring 52 from the position shown in Fig. 1 and into the position shown in Fig. 1a to move land 50 of said plunger valve to the right of port 54 and thus place the chamber 21 in communication with the chamber 19 through the ports 54 and 55 and the plunger valve chamber 47. Consequently the incoming line pressure is by-passed from chamber 19 to chamber 21 and thence to exhaust to reduce the pressure acting on the upper side of the piston 11 and thus to decrease the rate of lowering movement of the piston 11 and the element 13.

Theoretically the hydraulic medium below the piston 11 under the conditions just referred to is trapped and the downward movement of the piston would cease. However, this condition is a momentary one, since as soon as the land 36 of the plunger valve 35 has moved to the position shown in Fig. 1a, the pressure of the hydraulic medium in chamber 42 quickly falls to a point where the spring 39 shifts the plunger valve to its normal position of Fig. 1. Also at this time the spring 52 functions to shift the plunger valve 43 from the position of Fig. 1a to its normal position of Fig. 1. Therefore the chamber 20 after being momentarily closed from communication with the chamber 42 is again in communication therewith while the chamber 19 after being momentarily in communication with the chamber 21 is again out of communication therewith and full line pressure is flowing to the upper side of the piston.

It will be understood that during the lowering operation of the motor the pressure in chamber 42 is maintained substantially constant since the discharge area for the hydraulic medium in said chamber 42 is of a predetermined size by the adjustment of the needle valve, thereby allowing the medium to flow from the chamber 42 to the chamber 21 at a substantially uniform rate.

Consequently the lowering movement of the piston of the motor 10 is substantially at a uniform predetermined rate, irrespective of the load imposed on the piston during such lowering movement.

When it is desired to operate the motor 10 in the raising direction the selector valve body 27 is placed in registry with the port 25, whereupon line pressure flows through the line 23 and into the chamber 21. A negligible portion of this pressure will flow from the chamber 21 through the port 44 around the needle valve, through chamber 42, ports 41 and 40 into the chamber 20. However, the hydraulic pressure medium in chamber 21 acting on valve 61 will overcome the weak spring 62 and unseat said valve and hence the major portion of the medium following the line of least resistance will flow from the chamber 21 through the port 59 directly into the chamber 20 from whence it flows through line 17 to the underside of the piston 11. At this time the cylinder of the motor above the piston is being exhausted through line 16, chamber 19, line 22, and through the selector valve to discharge. At all times during the raising operation of the motor the plunger valves 35 and 43 remain in their normal positions as shown in Fig. 1. The raising movement being effected at full line pressure is more rapid than the substantially uniform lowering movement of the piston of the hydraulic motor and consequently the element actuated by the motor is raised more rapidly than it is lowered.

The term "chamber" as used herein to designate the enclosed spaces 19, 20, 21, 34, 42 and 47 in the housing 18 is intended to include any enclosed space such as a bore, a compartment, a passage, a cavity or the equivalent. For convenience and to render the claims more readily understandable the chambers 19, 20, 21 and 42 will be referred to in the claims, respectively, as "through passage," "flow chamber," "cavity" and "pressure chamber." Although valves 35 and 43 have been shown and described as plunger valves, it will be understood that various other form of valves subject to the pressure in pressure chamber 42 might be employed in their place and used to accomplish the same purposes as do said plunger valves.

Although a preferred embodiment of the invention has been illustrated and described herein it will be understood that the invention is susceptible of various modifications and adaptations within the scope of the appended claims.

Having thus described my invention I claim:

1. In a hydraulic power system, in combination, a hydraulic motor for effecting the raising and lowering of a movable element of an apparatus and including a cylinder and a piston movable therein, a hydraulic circuit adapted to be connected to a source of hydraulic pressure and including a direction selector valve and a hydraulic control valve in said circuit intermediate said selector valve and said motor, said control valve comprising a housing having therein a flow chamber and a through passage, said chamber and said passage being connected respectively by said circuit to said motor on opposite sides of the piston thereof, said passage being connected by said circuit to said selector valve, a cavity in said housing and connected by said circuit to said selector valve, a pressure chamber in said housing, means in said housing providing communication between said pressure chamber and said flow chamber, pressure actuated valve means operatively associated with said last means for controlling

communication between said chambers and normally held in open position by a predetermined force and subject to the pressure in said pressure chamber to be moved thereby when said pressure exceeds said force to diminish the communication between said chambers, means placing said pressure chamber and said cavity in communication, a valve controlling the effective area of said communication between said pressure chamber and said cavity, means placing said passage and said cavity in communication, and a pressure actuated valve operatively associated with said last means and normally held in closed position by a predetermined force and subject to the pressure in said pressure chamber to be moved thereby when said pressure exceeds said force to establish communication between said passage and said cavity.

2. A hydraulic power system as defined in claim 1 and wherein said housing is provided with a bore closed at its outer end and having its inner end communicating with said cavity, said bore being provided with a valve seat adjacent its inner end, means located intermediate the inner and outer ends of said bore and placing said bore in communication with said flow chamber, a valve in said bore, and means maintaining said latter valve against said seat with a predetermined pressure whereby when said cavity is subject to full line pressure said valve in said bore is unseated and the incoming hydraulic pressure is by-passed from said cavity through said bore to said flow chamber from whence it passes to said motor.

3. In a hydraulic power system, in combination, a hydraulic motor for effecting the raising and lowering of a movable element of an apparatus and including a cylinder and a piston movable therein, a hydraulic circuit connected to said motor and adapted to be connected to a source of supply of hydraulic pressure and including a direction selector valve and a hydraulic control valve located intermediate said motor and said selector valve, said control valve comprising a housing having therein a flow chamber connected through said circuit to said motor on one side of the piston while said motor on the opposite side of the piston is connected through said circuit to said selector valve, a cavity in said housing and connected through said circuit to said selector valve, a plunger valve chamber in said housing, means placing said plunger valve chamber in communication with said flow chamber, a pressure chamber in said housing, means placing said pressure chamber in communication with said valve chamber intermediate the ends thereof and with said cavity, a valve controlling the effective area of communication between said pressure chamber and said cavity, a plunger valve mounted in said valve chamber and normally maintained by a predetermined force in a position wherein communication exists between said valve chamber and said flow and pressure chambers, and additional means providing communication between said pressure chamber and an end of said valve chamber whereby whenever pressure builds up in said pressure chamber exceeding said predetermined force said plunger valve is shifted causing reduction of communication between said flow and pressure chambers.

4. A hydraulic power system as defined in claim 3 and wherein said housing is provided with a bore closed at its outer end and having its inner end communicating with said cavity, said bore being provided with a valve seat adjacent its inner end, means located intermediate the inner and

outer ends of said bore and placing said bore in communication with said flow chamber, a valve in said bore, and means maintaining said valve against said seat with a predetermined pressure whereby when said cavity is subject to full line pressure said valve in said bore is unseated and the incoming hydraulic pressure medium is by-passed through said bore from said cavity to said flow chamber from whence it passes to said one side of the motor piston.

5. In a hydraulic power system, in combination, a hydraulic motor for effecting the raising and lowering of a movable element of an apparatus and including a cylinder and a piston, a hydraulic circuit connected to said motor and adapted to be connected to a source of supply of hydraulic pressure and including a direction selector valve and a hydraulic control valve located intermediate said motor and said selector valve, said control valve comprising a housing having therein a flow chamber and a thorough passage, said flow chamber and said passage being connected respectively to said motor through said circuit on opposite sides of said piston, said passage being connected through said circuit to said selector valve, a cavity in said housing and connected through said circuit to said selector valve, a plunger valve chamber in said housing, means placing said plunger valve chamber in communication with said flow chamber, a second plunger valve chamber in said housing, means placing said second plunger valve chamber in communication with said passage and said cavity, a pressure chamber in said housing, means placing said pressure chamber in communication with said first plunger valve chamber intermediate the ends thereof and with said second plunger valve chamber adjacent an end thereof and with said cavity, a valve controlling the effective area of communication between said pressure chamber and said cavity, plunger valves mounted in said plunger valve chambers and normally maintained by a predetermined force in positions wherein communication exists between said first plunger valve chamber and said flow and pressure chambers and is interrupted between said second plunger valve chamber and said cavity, and additional means providing communication between said pressure chamber and an end of said first plunger valve chamber whereby whenever pressure builds up in said pressure chamber exceeding said predetermined force both of said plunger valves are shifted causing interruption of communication between said flow and pressure chambers and placing said passage and said cavity in communication through said second plunger valve chamber.

6. A hydraulic power system as defined in claim 5 and wherein said housing is provided with a bore closed at its outer end and having its inner end communicating with said cavity, said bore being provided with a valve seat adjacent its inner end, means located intermediate the inner and outer ends of said bore and placing said bore in communication with said flow chamber, a valve in said bore, and means maintaining said latter valve against said seat with a predetermined pressure whereby when said cavity is subject to full line pressure said valve in said bore is unseated and the incoming hydraulic pressure medium is by-passed through said bore from said cavity to said flow chamber from whence it passes to said motor.

7. A hydraulic power system as defined in claim 5 and wherein said valve that controls the effective area of communication between said pres-

9

sure chamber and said cavity is an adjustable valve having provision for manually seating the same in different adjusted positions to vary the said effective area of communication.
